UNITED STATES PATENT OFFICE

LEVI S. LONGENECKER, OF PITTSBURGH, PENNSYLVANIA

METALLURGICAL FURNACE

Application filed October 18, 1927. Serial No. 237,115.

This invention relates to refractory blocks such as used in building metallurgical furnaces and more particularly, although not necessarily, to blocks for use in constructing roofs for open hearth furnaces and other places where the blocks are subjected to high temperatures and means for supporting such blocks.

An object of this invention is to produce an improved block or tile of the characteristics indicated, provided with means for uniting a series of blocks together in such a way that if one or more of the same are broken, the portion will be prevented from falling out of the roof or other structure in which the blocks are placed; and also provide with means for supporting a plurality of series of blocks in such a manner that shall permit relative movement of each series of blocks with respect to its adjacent series of blocks during expansion and contraction of the said blocks caused by the heat subjected thereto.

Another object of this invention is to provide a furnace roof composed of refractory blocks and means for supporting the blocks, without the use of skewbacks or side retention, in a proper sloping position, and means for predetermining any degree of slope that may be desired.

A further object of this invention is to provide means for supporting a plurality of such series of blocks having means for adjusting each series of blocks with respect to the adjacent series of blocks.

A still further object of this invention is to provide means for supporting such blocks or tiles that shall be simple and inexpensive to manufacture and greatly expedite the installation of a metallurgical roof or other places where such blocks may be employed.

Other objects reside in the novel construction, design and combination of parts described in the following specification and illustrated in the accompanying drawings wherein a practical embodiment of the inven-

tion is represented and in which similar characters of reference indicate corresponding parts of all views.

Figs. 1 and 2 are perspective views of a block embodied in the invention taken at 180° one to the other.

Fig. 3 is a perspective view of a pair of blocks showing the manner in which the yoke hooks are applied to the blocks.

Fig. 4 is a perspective view of a portion of a furnace roof or arch composed of blocks and the supporting means constructed in accordance with the invention.

Fig. 4a is an end view of the rows of suspended blocks shown in Fig. 4, showing the off-center hanging of the rows.

Fig. 5 is an elevational view of a portion of a furnace roof or arch showing the position taken by the blocks when expanded by heat from the furnace.

Fig. 6 is a similar view to Fig. 5, showing the contracted position of the blocks before being subjected to heat.

Fig. 7 is an enlarged fragmental view of a support and an adjustable hanger from which blocks are suspended off-center with reference to the support.

Patent 1,590,303 issued to me under date of June 29, 1926, discloses the interlocking features which are employed in the present block embodied in this invention. According to this invention I provide a block having the interlocking features mentioned above together with means for supporting such blocks or tiles which permit easy construction of a roof from such blocks and permit relative movement between the various series or sections of blocks in such a manner as to relieve the roof from the compression and strain caused by the expansion of the blocks when subjected to heat. It will be obvious that either a flat or sprung suspended interlocking furnace roof may be constructed from the blocks herein described. The present invention shows added features relative to

interlocking the blocks i. e., the provision of interlocking means for all four faces of each block so that each block will interlock laterally as well as longitudinally with adjacent blocks.

In the drawings, 1 is a refractory block which may be either rectangular in shape as illustrated, or may have one or more sides tapered to any predetermined degree in order 10 to construct a roof of any desired shape. The block 1 is provided on one of its sides or faces with a tongue or projection 2 of inverted V-shape. The opposite side or face is provided with a groove 3 of V-shape and of substantially 15 the same dimensions as the tongue or projection 2, the projection or tongue 2 being adapted to engage the groove 3 of an adjacent block 1 for preventing the falling away of broken parts of the blocks as fully described 20 in the above mentioned patent. At the upper portion or end of the block 1 and directly above the projection 2 is provided a groove 4, the bottom of said groove being curved upwardly and terminating at the top 25 face of the block near the center thereof. The purpose of groove 4 will hereinafter be described. The block 1, as shown, has a slot 5 located directly above the groove 3 which is deeper and extends slightly further into 30 the block than the groove 3. The slot 5 merges into a slot 6 that terminates at the top face of the block 1, the slot 6 being narrower and shallower in depth than the slot 5, the purpose of which will hereinafter be described.

The block 1 is also provided with a tongue or projection 7 of V-shape disposed on an edge or third side and a groove 8 of like shape on the opposite edge or fourth face.

40 Since the opposite edges or opposite faces of each of the blocks 1 are provided with tongues and grooves, the tongues of one block will register and interlock with the grooves of adjacent blocks of the same row and also 45 of the adjacent rows when the blocks are laid up in rows as illustrated in Fig. 4.

The blocks or tiles shown in the drawings are relatively thin and it will be understood that the tongue and groove construction is 50 intended to be applied to all other shapes of blocks and tiles which make up a full line of refractories.

Fig. 3 illustrates yoke hooks 8', one for each block. The yoke hook 8' is of U-shape, 55 one arm of which is slightly longer than the other, the shorter arm 9 terminating in a T-shape portion 11 having a tapered side 12. The longer arm 13 terminates in a hook-shaped portion 14 forming a groove 15, the 60 contour of which is substantially the same as the contour of the outer faces of the T-shaped portion 11 on the arm 9. The groove 15 is adapted to receive the portion 11 of the adjacent yoke hook 8' as is shown at 65 in Fig. 3.

In attaching the yoke hooks 8' to the blocks 1 the hooks are so placed over the upper ends of the blocks that the T-shaped portion 11 of the hook 8' is received in the slot 5 and the hook portion 14 of the yoke hook is received 70 by the groove 4 on the opposite side.

The bottom of groove 4 is curved inwardly as indicated at 17 for permitting the portion 14 of the hook to pass to the lowermost portion of the groove 4 since the distance between the face 12 of the portion 11 and the adjacent face of the arm 13 is less than the thickness of the block 1. The inwardly curved bottom 17 of groove 4 permits the portion 14 of the arm 13 to pass to the lowermost portion of the groove 4.

75 It can be seen from the drawings that the slots 5 and 6 form shoulders 18 at the upper portion of the slot 5. These shoulders rest upon bearing face 19 of T-shaped portion 11 of the hooks 8' so that each block is suspended from the portion 11 of the hook. Since the slot 5 is of greater depth than the slot 6, the inner portion 20 of the upper face 19 of the portion 11 has a bearing surface 21 extending 80 substantially the full width of the slot 5.

85 The block is therefore supported off-center by the T-shaped portion engaging and cooperating with the slot 5 and the shoulders 18. This off-center arrangement of the hanger gives to each block a natural slope or bias 90 toward the center of the arch or ring as will be better understood as the specification progresses.

95 Fig. 4 illustrates a portion of a furnace roof 100 showing the manner in which the blocks are to be installed. The roof 22 is supported by hooks 23 each of which are provided with a J portion 24 at their lower ends for engaging a yoke 8' and an adjustable nut 24 and clip 105 25 at its upper portion for adjustably connecting the roof to an over-head supporting structure made up from suitable structural members as shown at 26 and 27. The supporting member 26 is preferably of such form 110 as to adapt it to support a pair of rows of blocks of substantially arch or arc form as shown in Fig. 4. The width of the bottom of the supporting member 26 is slightly less than the distance between the yoke hooks of 115 the adjacent rows. This causes adjacent rows to be urged, by gravity, towards each other and hang close together and yet permits relative movement therebetween during expansion and contraction caused by different temperatures to which the roof may be subjected. As is apparent from Figs. 4 and 4a, the rows of blocks suspended from opposite sides of member 26, are biased by gravity towards a 120 vertical or perpendicular plane passing through the longitudinal axis of support 26.

125 This construction also permits the swinging apart of adjacent rows as well as the swinging apart of the sections or series of 130

blocks or tiles for replacing such blocks or tiles as may become damaged.

Referring to Figs. 5 and 6 which illustrate an elevational view of one ring of a metallurgical roof constructed in accordance with the invention, each row is adapted to be built up from its center indicated at 28. A pair of hooks 23 are attached to the supporting member 26 by means of the clips 25 and a pair of blocks 1 provided with yokes 8' are positioned on the J portions of the hooks 23 in oppositely disposed position. The J portions 24 engage the yokes 8' at their adjacent sides. Since the blocks 1 are oppositely disposed and supported off-center by the portion 11 of the yokes 8', the lower portion of the blocks will tend to slope toward the center of the ring as shown in Fig. 6 at 29. A series of blocks are then built up in the manner shown by Fig. 3; viz., the portion 11 of each adjacent yoke 8' is positioned in the groove 15 of the corresponding yoke 8'. In this manner it can be seen that one hook 23 may be employed to support a predetermined number of blocks 1 which I term a series or section of blocks. Obviously, the blocks will slightly droop downwardly as the weight increases on the hook 23. Therefore the beginning of a new series or section of blocks supported by another hook 23 will be slightly higher than the last block of the adjacent series of blocks. In this manner a roof is constructed of any desired length and any number of rows may be disposed side by side to give the roof any predetermined width. Since each block 1, beginning with the block suspended by its yoke 8' from a J-hook 23, is supported by its yoke 8' from the yoke 8' of an adjacent block, in the manner indicated, each block is hung off-center with respect to the center of gravity thereof, so that each block is urged by gravity into positive engagement with an adjacent block, as indicated by the arrow and its accompanying legend of Fig. 3.

Thus, the blocks in each row illustrated in Figs. 4, 4a, and 5, are biased in two directions as indicated by the legends and arrows appearing on the drawings.

Such a roof is easily and expediently installed without the use of cement and without the hazard of blocks dropping out. The builder has the use of both hands at all times as it is only necessary to engage the blocks one onto the other as above described.

This construction causes all of the blocks to naturally slope toward the center of each row and thereby maintains at all times close contact relation with one another at the bottom portion of the roof, the value of which is obvious to those acquainted with metallurgical furnaces.

Another advantage of this construction is manifest by the relative sliding action between cooperating series or sections of blocks during the expansion or contraction of the

blocks when subjected to different temperatures. As stated above, Fig. 6 shows the position of the blocks when they are contracted due to normal temperature, and, Fig. 5 illustrates the position of the blocks when expanded due to heat. As the blocks expand the sections of course expand and swing the adjacent sections outwardly. This expansion causes the outer ends of the sections to move outwardly and upwardly so that when the blocks are in full expanded position the roof is in complete alignment.

It can be seen from the above that since no skewbacks or end supports are provided for the roof, the rows are free to swing in any direction as the compression due to expansion may dictate. This prevents the breaking of tiles and greatly prolongs the life of the roof.

Other advantages lie in the simple and rugged construction of the roof and the inexpensive manufacture of the tiles and supporting means.

While I have illustrated and described but one embodiment of this invention it will be apparent to those skilled in the art that certain changes, modifications, substitutions, additions and omissions may be made in the apparatus described without departing from the spirit and scope of the appended claims.

What I claim as new and desire to secure by Letters Patent is:

1. A furnace roof composed of refractory blocks arranged side by side and interconnected by means of tongues and grooves of general triangular form and having their apexes uppermost and a swinging means for supporting the said blocks, the said means permitting relative movement between the adjacent faces of the blocks during expansion and contraction thereof.

2. A furnace roof composed of refractory blocks, a U-shaped hook for engaging each block, the said hook having a portion for receiving a cooperating portion of each adjacent hook and means for engaging one of said hooks for supporting a plurality of blocks.

3. A furnace roof composed of a plurality of series of refractory blocks, each block of said series being provided with a U-shaped hook having a portion for engaging an adjacent hook and for supporting an adjacent block and a single means for supporting each series of blocks.

4. A furnace roof composed of a plurality of series of refractory blocks, each block of each series being provided with a U-shaped hook for meshing an adjacent block, and adjustable means for engaging the hook of one of said blocks for supporting the series of blocks.

5. A furnace roof including a plurality of rows of refractory blocks, each row composed of a plurality of sections of refractory blocks, each block of the said sections

being provided with a U-shaped hook, and a single means for engaging one of the said hooks of each section for supporting the section.

5. 6. A furnace roof including a plurality of rows of refractory blocks, each row composed of a plurality of sections of refractory blocks, each block of the said sections being provided with a U-shaped hook, and a 10 swinging means for engaging one of the said hooks for supporting each section whereby the sections are permitted to swing in any direction that may be dictated by expansion or contraction of the blocks during different 15 temperatures.

7. A furnace roof composed of a plurality of sections of refractory blocks, each block of a section being provided with a support, the said support having a portion for cooperating with a hook engaging portion of an adjacent block of the said section and means for supporting each of said sections.

8. A furnace roof composed of a plurality of series of refractory blocks, each block of 25 a series being provided with a support, each of said supports having a portion for engaging and cooperating with an adjacent support of said series in such a manner as to permit relative sliding action between adjacent blocks of said series during expansion or contraction of the said blocks.

9. In a furnace roof, the combination with a plurality of series of refractory blocks, of a swinging means for supporting each of the said series in side by side relation, the said means comprising a U-shaped yoke having a T-shaped portion for engaging each block on the upper portion of one of its sides and a J-shaped portion for engaging a groove in the said block on the opposite side to the T-shaped portion, the said J-shaped portion engaging and cooperating with the T-shaped portion of each adjacent block and a hook for engaging one 45 yoke of each series for supporting the said series.

10. A furnace roof including a plurality of sections of refractory blocks, a separate support for each block of a section, each of 50 said supports having a portion for supporting its block from the support of an adjacent block of the same section, and means for supporting each of said sections.

11. A furnace roof including a plurality of 55 sections of refractory blocks, and a separate support for each of said blocks, each of said supports having a portion for supporting its block therefrom and a portion for engaging the support of an adjacent block to thereby 60 support said block and its support from the support of said adjacent block.

12. A furnace roof including a plurality of 65 sections of refractory blocks, and independent support for each of said blocks, each of said supports having a portion from

which its block is supported and having a portion for engaging the support of an adjacent block of the same section, and means for supporting each of said sections.

13. In combination, a support, a group of 70 blocks laid up in a row, hanging means for each block, means for hanging one of said blocks from the support, and means for supporting each of the other blocks in said group from the hanging means of an adjacent block. 75

14. A suspended refractory structure comprising a plurality of blocks, suspending means for each block and means suspending each block from the suspending means of an adjacent block. 80

15. In a structure comprising a plurality of blocks, in combination, a support, blocks arranged in adjacent rows, means for suspending the blocks of each row off center from the support so that adjacent faces of 85 the blocks in each adjacent row are biased towards a perpendicular passing through the support, and means for so suspending each block of each row that the blocks are biased in a direction longitudinally of said row. 90

16. A suspended refractory structure comprising a group of blocks, a support, means for suspending said blocks from the support as a group, and detachable means for supporting each block on the detachable means 95 of an adjacent block.

17. A furnace roof composed of refractory blocks, a supporting member for engaging each block, the said member having a portion for receiving a cooperating portion of 100 each adjacent supporting member and means for engaging one of said supporting members for supporting a plurality of blocks.

18. A suspended refractory structure composed of refractory blocks and a supporting 105 member for each block, each supporting member having a portion thereof disposed to receive a cooperating portion of an adjacent block supporting member, one of said supporting members being disposed to carry the 110 load of said blocks.

19. A suspended refractory structure composed of refractory blocks each having a recess in a face thereof, and a support for each block, each support having a portion of T- 115 shape adapted to register in the recess of its associated block, each support also having a portion thereof disposed to receive a cooperating portion of an adjacent block supporting member.

20. A suspended refractory structure composed of refractory blocks each having a recess of T-shape in a face thereof, and a support for each block, each support having a portion adapted to register in the recess of 125 its associated block, each support also having a portion thereof disposed to receive a cooperating portion of an adjacent block supporting member.

21. A block supporting member having a 130

portion from which a block may be suspended, and another portion adapted to engage a complementary portion of an adjacent supporting member, so that when a series of such supporting members are assembled in operative relation from a starting point, each supporting member is carried by its adjacent supporting member and all the supporting members of the series beyond the first supporting member are carried by the first supporting member.

In testimony whereof, I have hereunto subscribed my name this 26th day of September, 1927.
